UNITED STATES PATENT OFFICE.

WALLACE I. STIMPSON, OF MILFORD, MASSACHUSETTS, ASSIGNOR TO DRAPER COMPANY, OF HOPEDALE, MASSACHUSETTS, A CORPORATION OF MAINE.

FILLING-CARRIER FOR LOOM-SHUTTLES.

SPECIFICATION forming part of Letters Patent No. 764,214, dated July 5, 1904.

Application filed January 22, 1904. Serial No. 190,122. (No model.)

To all whom it may concern:

Be it known that I, WALLACE I. STIMPSON, a citizen of the United States, residing at Milford, in the county of Worcester and State 5 of Massachusetts, have invented an Improvement in Filling-Carriers for Loom-Shuttles, of which the following description, in connection with the accompanying drawings, is a specification, like characters on the drawings 10 representing like parts.

This invention relates particularly to filling-carriers for loom-shuttles of the type wherein the head of the filling-carrier is provided with annular ribs or projections to be 15 engaged and held in position in the shuttle by separable spring-jaws mounted in the shuttle. Usually such projections are made as split metallic rings seated in shallow annular grooves in the head of the filling-carrier 20 and by their spring action remaining in position. The filling-carriers or bobbins are generally made of wood, and very considerable trouble has been experienced by the loosening of the metallic rings on the head of 25 the filling-carrier due to shrinkage of the wood, so that the filling-carrier must be provided with new rings or wholly discarded. The dampening of the yarn causes the wood to swell, expanding the rings, and when the 30 wood dries out it shrinks, the constant changes thus produced alternately causing so much looseness of the rings that the filling-carrier will not be held properly in the shuttle.

My present invention has for its object the 35 production of simple and effective means for overcoming the effects of swelling or shrinking of the wood of the filling-carriers, so that the rings will always have a firm hold on the head.

Figure 1 is a side elevation of a filling-carrier embodying one form of my present invention. Fig. 2 is a longitudinal section thereof on the line 2 2, Fig. 1; and Fig. 3 is a sectional detail of the head before the reinforce 45 is applied thereto.

The filling-carrier or bobbin F, of well-known construction and usually made of

wood, is provided with a tubular head F', its external surface having annular shallow grooves f formed therein (see Figs. 2 and 3) 50 between the outer end of the head and the shoulder f^x between the opposite end of the head and the barrel of the bobbin. As shown in Figs. 2 and 3, the outer end of the head is counterbored, as at f', the head tapering externally toward such outer end, and in longitudinal section the head presents a corrugated exterior. The grooves f alternate with ribs or projections f² to present the corrugated surface. A thin metallic sleeve or reinforce 60 1 is applied to and surrounds the head and is suitably compressed thereupon to conform to the external configuration of the head, whereby annular depressions or seats 2 are formed in the sleeve. Metallic spring or split rings 65 3 are snapped into the seats 2, being separated by the higher portions or ribs 4 of the sleeve, which latter acts as a reinforce for the head and a firm support for the rings. The metal sleeve cannot shrink and retains its 70 original size and contour irrespective of the shrinkage of the material of the bobbin, so that the rings 3 will always have a firm hold or grip. I effect the compression of the metal sleeve 75 very easily and conveniently by spinning it upon the bobbin-head, and the outer end of the sleeve is preferably overturned and spun into the counterbored outer end of the head, as clearly shown at 5, Fig. 2. The sleeve is thus made to conform to the external configuration of the head and cannot move longitudinally thereon. In order to prevent any rotative movement of the sleeve should the bobbin shrink abnormally, I may by a prick-punch upset and drive into the material of 80 the head a bur or prong 6, as shown in the drawings. The metallic sleeve or reinforce is made of thin and light metal, and so adds very little to the weight of the bobbin, while the life of the latter is thereby greatly increased, 85 for so long as the rings 3 have a firm hold on the head they will act properly when engaged by the jaws in the shuttle. The reinforce also serves to brace and strengthen the head of the 90

filling-carrier and practically obviates any tendency thereof to split.

Modifications or changes may be made by those skilled in the art without departing from the spirit and scope of my invention, one practical embodiment thereof being herein shown and described.

Having described my invention, what I claim, and desire to secure by Letters Patent, is—

1. A non-metallic filling-carrier for loom-shuttles having a metal sleeve surrounding and secured to its head and provided with external annular seats, and metallic holding - rings 15 mounted in said annular seats.
2. A non-metallic filling-carrier for loom-shuttles having a thin metal sleeve surrounding and compressed upon its head and provided with external annular seats, and metallic split 20 rings snapped into the seats.
3. A non-metallic filling-carrier for loom-shuttles having its head annularly corrugated externally, a thin metal sleeve surrounding and conforming to the external contour of the 25 head, to present alternating annular depressions and ribs, and metallic holding - rings seated in the depressions.
4. A non-metallic filling-carrier for loom-shuttles having its head annularly corrugated 30 externally, a thin metal sleeve surrounding and spun upon the head to conform to the contour thereof, and metallic rings sprung into the

seats formed by the annular depressions in the sleeve.

5. A filling-carrier for loom-shuttles, having its head provided with a plurality of annular grooves, a metallic sleeve surrounding and compressed upon the head to conform to the configuration of its external surface, and metallic rings seated in the annular depressions thereby formed in the sleeve. 40

6. A wooden filling-carrier for loom-shuttles, having a tubular head provided with annular grooves and counterbored at its outer end, a metal sleeve surrounding and compressed upon the head to conform to its contour and inturned around its counterbored end, and metallic spring-rings seated in the annular depressions presented by the sleeve. 45

7. A wooden filling-carrier for loom-shuttles having its head annularly corrugated, a metallic reinforce surrounding and spun upon the head to conform to its configuration, means to prevent rotation of said reinforce on the head, and metal rings seated in the seats formed 50 by the annular depressions in said reinforce. 55

In testimony whereof I have signed my name to this specification in the presence of two subscribing witnesses.

WALLACE I. STIMPSON.
